INTERNAL COMBUSTION ENGINE

Johann Mahler, Augsburg, Germany, assignor to
 Maschinenfabrik Augsburg-Nürnberg A.-G.,
 Augsburg, Germany, a corporation of Germany

Application January 16, 1933, Serial No. 651,881
 In Germany January 26, 1932

4 Claims. (Cl. 123—195)

This invention relates to internal combustion engines.

One object of the invention is the provision of an engine cylinder construction so arranged as to afford quick and ready disassembly and lateral removal of an engine cylinder after disconnecting it from the cylinder head.

Another object of the invention is the provision of an engine having cylinders that can be readily disconnected from the engine crank case and from the cylinder head and removed laterally without disturbing the connection between those parts.

A further object of the invention is the provision of an engine cylinder arrangement, one end of the cylinder being detachably secured to a cylinder head while the other end of the cylinder is received in a sectional enclosing member detachably fastened to the engine crank case and readily removed therefrom to enable the cylinder to be received in the opening in the crank case so that the cylinder can be readily disconnected from both the cylinder head and the engine crank case without disturbing the relative positions of the latter.

Other objects and advantages of the invention will be apparent from the following description, the appended claims and the accompany drawing, in which—

Fig. 1 is a view of an engine embodying the present invention shown partly in central vertical section;

Fig. 2 is a side elevation of the engine;

Fig. 3 is a horizontal section on the line 3—3 of Fig. 1.

Fig. 4 is a section on the line 4—4 of Fig. 1 with the piston and its connecting rod omitted.

Referring more particularly to the drawing by reference letters, *a* designates the base or crank case frame of a single acting engine, herein shown as of the multiple cylinder stationary type. Vertical columns or rods *c* rigidly interconnect the base *a* with the cylinder head structure *d*. The various cylinder heads of the engine may either be cast all in one piece, or welded or otherwise secured rigidly together. The cylinder heads contain the various valves *p*. An oil pan *b* is detachably secured to the lower side of the base *a*.

The various cylinders *e*, at their upper ends, are individually detachably secured to the lower side of the cylinder head structure *d*. The upper ends of the cylinders are preferably flanged outwardly, and these flanges are bolted to the cylinder head structure from below by bolts *s*. The lower end of each cylinder is held in its proper

position with respect to the crank case by an enclosing means shown in the form of rings secured by bolts *q* on the upper crank case wall *h*. Each encircling ring and the cylinder are relatively movable in an axial direction, so that the ring can be moved up on the cylinder, the ring being preferably sectioned or split into two parts *f*¹ and *f*², as shown, so that these parts can be readily withdrawn laterally. The two parts of the ring are seated in an opening *g* in the crank case which is somewhat larger in size than the outside diameter of the lower cylinder end, as shown in Fig. 1. When the bolts *q* are removed, it will be apparent that the ring portions *f*¹ and *f*² may be moved upwardly a sufficient distance to permit their subsequent lateral withdrawal from both the cylinder and the crank case, leaving a space between the cylinder and the crank case. After disconnecting the bolts which secure the upper cylinder flanges to the cylinder head structure *d*, a cylinder may be moved down partly into the opening *g* in the crank case, and then tilted laterally to the position shown in the dot and dash lines in Fig. 1. The cylinder may then readily be withdrawn entirely, this disassembly taking place without disturbing the normal position of the cylinder head structure *d*, or its normal relationship with respect to the crank case.

The upper portion of each cylinder is provided with a chamber *i* for cooling liquid, having suitable fluid connection with a cooling chamber provided in the cylinder head structure. Cooling liquid is supplied to the chamber *i* by means of a sectional pipe, the various T-shaped pipe sections *j* being connected by means of flanges *k* between which are preferably packing rings of rubber or the like. The connected pipes form a common conduit for the supply of cooling liquid to the various chambers *i*, but when it is desired to remove any cylinder it will be apparent that the flanges *k* of the pipe of that particular cylinder may be readily unbolted from the adjacent pipes to permit the lateral withdrawal of the cylinder.

Each part *f*¹ *f*² of a cylinder enclosing ring is provided with a section of an oil baffle plate, the oil baffle section *n* being welded, bolted or integrally formed with the section *f*¹ while the plate portion *n*¹ is similarly provided on the section *f*². An opening *o* is provided in the two baffle plates *n* *n*¹ through which the connecting rod *m* extends, the baffle plate serving to a large extent to prevent the passage of oil from the crank case up onto the cylinder walls and thus into the combustion chamber. The plates *n* *n*¹ are of course removed with

the ring sections $\frac{1}{4}$ $\frac{1}{2}$ during the disassembly of a cylinder.

After a cylinder has been removed from the engine, if desired, the piston can be disassembled from the connecting rod, and the connecting rod itself can be readily separated by removing the screws which attach the split bearing portions together, the space g provided in the crank case being sufficiently large to permit the withdrawal of the connecting rod through it even where the crank pin diameter is large as in a high speed engine. The various parts can be readily reassembled by carrying out the same operations as above described but in a reverse order.

5 In accordance with this invention it will be apparent that the disassembly of any cylinder; or of any cylinder, piston and piston rod may be accomplished very quickly without disturbing the normal relationship of the cylinder head with respect to the base or crank case. Such an arrangement is particularly desirable where there is very little space between the top of the engine and the ceiling as such limited room conditions are not objectionable where the cylinder is removed in a lateral direction. The cylinder arrangement, however, is applicable to any condition in which the removal or disassembly of the parts in a very short time is desirable. For example the construction permits the quick removal of the cylinder in a very simple manner to facilitate the replacement or grinding of the valves without loosening the connection between the cylinder head and the engine crank case.

35 While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. An engine comprising a crank case having relatively immovable crank case walls, a cylinder head, means securing said crank case to said cylinder head, an engine cylinder having at one end a detachable connection to the cylinder head, and a ring encircling the other end of the cylinder and upwardly removable from but detachably secured to the crank case, said crank case having an opening in line with the cylinder of such size 10 as to receive the lower end of the cylinder in an inclined position while the crank case walls remain undisturbed and enabling the cylinder to be moved downwardly and then inclined so as to be separated from both cylinder head and crank 15 case.

2. An engine comprising an engine base, a cylinder head supported therefrom, an engine cylinder having at one end a detachable connection to the cylinder head, and a split ring detachably supported on the engine base and enclosing the other end of the cylinder and readily removable from both the crank case and cylinder.

3. An engine comprising an engine base, a cylinder head supported therefrom, an engine cylinder having at one end a detachable connection to the cylinder head, and a split ring axially movable on the cylinder and removably seated in the engine base, said base including a crank case wall having an opening of larger size than the 30 outside cylinder diameter for receiving the lower end of the cylinder in an inclined position.

4. An engine comprising a crank case, a cylinder head, means securing said crank case to said cylinder head, an engine cylinder having at one 35 end a detachable connection to the cylinder head, and a sectional ring detachably secured on the crank case and encircling the other end of the cylinder, the sections of the ring having inwardly extending oil baffle plate sections.

JOHANN MAHLER.
